PNEUMATICALLY ACTUATED
AUTOMOBILE JACKRobert A. Clay, 450 N. Parkway,
Scottsdale, Ariz. 85251

Filed July 22, 1969, Ser. No. 18,284

Term of patent 14 years

Int. Cl. D15—05; D12—14

U.S. Cl. D41—1

FIG. 1 is a perspective view of a pneumatically actuated automobile jack embodying my new design, the movable handle being shown in the folded, transport position;

FIG. 2 is a side elevation thereof;

FIG. 3 is a bottom plan view thereof; and

FIG. 4 is a side elevation thereof in partly inflated condition with the handle extended in position for use.

I claim:

The ornamental design for a pneumatically actuated automobile jack, as shown.
